UNITED STATES PATENT OFFICE.

SAMUEL CRUMP, OF NEW YORK, N. Y.

DESIGN FOR A LABEL.

Specification forming part of Design No. 6,326, dated December 24, 1872.

To all whom it may concern:

Be it known that I, SAMUEL CRUMP, of the city, county, and State of New York, have invented a Design for Labels, of which the following is a specification:

The nature of my design is fully represented in the accompanying prints, to which reference is made.

a is a scroll-figure of peculiar formation, the lower end of which, *b*, is bent and curled, as shown. This scroll forms the central figure of the design. Behind it, and divided by it, are two halves of a circle, formed in the following manner, viz: The center *f* is a solid black disk surrounded by gold, black, and white lines alternately. *c* is a solid gold or colored band bordered by black, white, and gold lines; the whole being surrounded by an ornamental scroll-border, *d*, substantially as shown. This completes the central portion of the design. The side *G* is a plain ground of gold or color surrounded by a border formed of one broad and two narrow lines, the former being in the

center and dotted with small white spots at close intervals throughout its entire length.

I propose to make this design in two or more forms, each form having one of the combination figures formed of the scroll *a b* and the half circles *f c d*, and one or more of the line and dotted borders *e*, as shown, and of various sizes, preserving in all the same general features and distinctive characteristics. I also intend to print it in various colors and combinations of colors; but in all cases preserving intact the scroll *a b*, the half circles and lines *f c d*, and the line and dotted border *e*, above described, which in all cases will be substantially the same.

What I claim as my invention is—

A design for labels formed of a combination of a scroll, two half circles, and a line and dotted border, substantially as shown.

SAM'L CRUMP.
